UNITED STATES PATENT OFFICE.

ANDREW J. DYGERT, OF PORTLAND, OREGON.

BINDER FOR MAGAZINES.

Application filed May 19, 1924. Serial No. 714,388.

To all whom it may concern:

Be it hereby known that I, ANDREW J. DYGERT, a citizen of the United States, and a resident of Portland, in the county of 5 Multnomah and State of Oregon, have invented a new and useful Binder for Magazines, of which the following is a specification.

This invention relates more particularly 10 to removable covers or binders for magazines, directories, and paper-bound books in general.

An object of my invention is to provide an exceedingly simple and efficient binder 15 which can readily be applied to any magazine of suitable dimensions.

A second object is to so construct the device 20 that once the magazine or book is put into place in the binder it is so securely held there that it must be intentionally released.

A third object is to so construct the device 25 that the dropping of the binder will not cause same to cut into the edges of the book.

A fourth object is to provide means for 30 ejecting the magazine or book from the binder when it is desired that this should be done.

I accomplish these results in the manner 35 set forth in the following specification and 30 illustrated in the accompanying drawing, in which:

Figure 1 is a longitudinal section taken 40 from behind one of the covers. Figure 2 is a longitudinal section taken along the line 35 2-2 in Figure 3. Figure 3 is an end elevation 45 of Figure 1. Figure 4 is a plan of Figure 1.

Similar numbers of reference refer to the same parts throughout the several views.

Referring in detail to the drawing, I have 40 applied my device to the inside of the back 10 of a pair of covers 11. Bound to the back 10 is a frame 12, preferably of wood. Each 45 end of the frame 12 is provided with a double slot adapted to receive the U-shaped standard 13 secured to the wooden frame 12 by means of the rivet or pin 14. On the inner side of the portions of the standards 13 which project above the frame 12 I have 50 formed the flanges 15 which serve as end stops for the pages 16 of the book being bound. I have also indicated the usual staples 17^a by means of which the pages 55 of the book are held together. Between the sides of each standard 13 is pivotally mounted on arm 17 on the pin 18. Each arm 17 is

provided with a notch 19 which corresponds with the notches 20 in the side of the standard 13.

A right angle spring 21 is secured to each 60 end of the frame 12 on its rear side by means of the screws 22. The spring 21 is provided with an inturned edge 23 which normally rests in the notches 20 of the standard 13 and when the arm 17 is depressed to the 65 position shown in Figure 2 while holding a book, the edge 23 also engages the notch 19 forming a latch which holds the arm 17 in its closed position. In order to release the 70 arm it is first necessary to withdraw the latching edge 23 from the notch 19 which is done by pulling the latch end of the spring 21 outwardly.

In order to facilitate the withdrawal of 75 the arm 17 from between the pages of the book after it is released by the withdrawal of the latching edge 23, I have provided the flat springs 24 whose forked ends 25 pass under the flanges 15 of the standards 13, and are held in place by the tack 26 which is 80 driven through the spring 24 into the member 12.

It is evident that as soon as the arm 17 is released that the spring 24 will push the 85 book away from the back of the binder causing the arm 17 to assume the position shown in Figure 1, leaving same ready for the introduction of the next book or magazine.

The operation of the binder is as follows: 90 When desiring to place one of these binders on a magazine the binder is opened up and placed on a flat surface with the arms 17 in the position shown in Figure 1. The magazine is then opened near its middle 95 point and placed between the flanges 15. The arms 17 are now pressed downwardly between the pages of the book, as shown in Figures 2 and 4, until the latch 23 falls into place, and that is all there is to it. The removal being effected by merely withdrawing one or both of the latches 23 and lifting the book out of the binder.

I am aware that many forms of binders have been constructed in the past, I therefore do not claim such devices broadly, but I do intend to cover such forms and modifications as fall fairly within the appended claims.

I claim:

1. In a binder, the combination of a binder back; a standard at one end of said back;

110

an arm pivoted to said standard, and a latch mounted on the same end of said back adapted to hold said arm parallel, thereto; said latch consisting of a spring arranged to 5 occupy registering notches in said arm and standard, when said arm is parallel to said back.

2. In a book binder, the combination of a rigid back member with a notched standard formed on the end thereof; a notched arm pivoted on said standard; a spring on said back, adapted to urge a book outwardly; and a spring latch adjacent to said standard adapted to engage the notches in said 10 arm and standard, and hold said arms parallel to said back.

3. A book binder having, in combination, a pair of covers; a back hinged between said covers; a frame mounted on said back; a 20 standard mounted at each end of said frame; an arm pivotally mounted on each of said standards and latch means adjacent to the pivot of each arm, for holding said arms inwardly parallel to said back without having said arms overlap and to permit same 25 to be released from the outside of said book.

4. A book binder having, in combination, a pair of covers; a back hinged between said covers; a frame mounted on said back; a standard at each end of frame; an arm 30 hinged on each standard; the ends of said arms not overlapping when parallel to said back and a short distance therefrom; said arms and standards having notches formed therein, which register when said arms are 35 parallel with said back and a spring latch adjacent to each standard adapted to fall into said notches and to hold said arms rigid.

5. In a binder, the combination of a frame; a U-shaped standard mounted on the 40 end of said frame, said standard having an arm pivoted between its open ends and having stop flanges formed on the inner edges of its open ends, said standard having notches formed therein; a similar notch 45 formed in said pivoted arm; a spring latch on said frame arranged to occupy the notches in said standard and arm at the same time; and a spring under said arm normally urging the binder contents outwardly.

ANDREW J. DYGERT.
